CASING FOR A FILMSTRIP PROJECTOR

Robert C. Zimmerman, Chicago, Ill., assignor to Bell & Howell Company, Chicago, Ill., a corporation of Illinois

Filed July 24, 1964, Ser. No. 80,993

Term of patent 14 years

(Cl. D61—1)

Fig. 1.

Fig. 2.

FIGURE 1 is a top front perspective view of a casing for a filmstrip projector showing my new design; and FIGURE 2 is a top rear perspective view thereof.

The bottom of the projector is substantially plain and unornamented except for the foot supports.

I claim:

The ornamental design for a casing for a filmstrip projector, as shown and described.
